[57] ABSTRACT

An open-circuit pneumatic timer of the type comprising an air intake filter, a timing device having a throttling channel, a bellows and connecting openings, wherein the filter is housed in a regulator shaped like a circular cupel, the bottom of which rests directly on the throttling channel and is provided with an opening cooperating with the said channel.

In this very simple and reliable timer, the distance covered by the fluid, outside the area where throttling is required, is kept to a minimum.

2 Claims, 2 Drawing Figures

FIG.1FIG.2## PNEUMATIC TIMER

This invention relates to a pneumatic timer whose components are specially designed to be housed in a box fitted with auxiliary contacts whose operation it is to defer for a certain time, the said box being generally designed to form part of a switching device such as a contact-maker, wherein several identical boxes are often mounted side by side. In some switching devices, timers are at present found wherein the fluid moves either in closed circuit or, conversely, in open circuit.

For example, in French Pat. No. 1,483,795 issued to the applicant, air circulates in closed circuit, which means that the filter cannot be positioned in the regulator; moreover, the bellows is separated from the regulator by the filter and by a considerable length of piping.

In U.S. Pat. No. 3,213,333(MIKINA), circulation is in closed circuit and the device is such that it has been possible to omit the filter; on the other hand, very careful sealing has been necessary, which has led to a substantial increase in the size of the device.

A known timing device of the type in which the fluid circulates in open circuit comprises, housed in a box, an air intake filter, a timing device equipped with a throttling channel whose effective length can be adjusted by means of a rotary regulator, a bellows expanding to a maximum volume under the action of an interior spring and channels enabling the fluid to pass through all these components.

There is no need to recall all the advantages of open-circuit pneumatic timers, but on the other hand it is worth mentioning that in earlier devices, the elements of change in their working, due to their very principle, have not always been taken into account.

Thus, air intake filters whose surface did not take sufficient account of short times have been in current use; moreover, the fluid was made to follow such tortuous paths that long times were often impaired after a few weeks' working. Moreover, it was often impossible to inspect or replace the filter without partially dismantling the timing device.

As an example of previous devices, U.S. Pat. No. 2,662,594 (SCHAEFFER) can be quoted.

In this American patent, the filter is positioned under the regulator, which made the device quite substantially more complex; moreover, the valve exhausting the air from the bellows is also positioned between the regulator and the bellows, which considerably decreases the effective volume of fluid and, consequently, narrows the range of setting times.

In French Pat. No. 1,153,769 (WESTINGHOUSE), the regulator carries no unit cooperating directly with the throttling circuits; moreover, the suggested filter is awkward to make and involves precision manufacture if the rotation of the regulator is not to damage the filter.

The object of the invention is to provide a pneumatic timer in which the above disadvantages are considerably reduced, by using a filter with the largest possible surface, bearing in mind the small bulk made necessary by the side-by-side mounting mentioned above, and in which measures have been taken for the distance covered by the fluid, outside the area where throttling is required, to be kept to a minimum. The pneumatic timer in accordance with the invention comprises, housed in a box, an air intake filter, a timing device equipped with a throttling channel the effecting length of which can be adjusted, a bellows expanding to maxi-

mum volume under the action of a spring, ports connecting all these components to one another and a rotary component regulating the length of the throttling channel, said component having an opening only separated from the inside volume of the bellows by the throttling channel and by another opening in a partition integral with the box and on either side of which there are the bellows on the one hand and the filter, the timing device and the regulator on the other hand, the regulator being shaped like a circular cupel, the open part of which houses the filter and the bottom of which, resting directly on the throttling channel, comprises the said opening cooperating with the channel.

Other characteristics and advantages of the invention will emerge clearly below. In the attached drawings:

FIG. 1 is a sectional view of a timer in accordance with the invention, and

FIG. 2 is a view from below, with the bottom of the box sides 1, a bottom 2 and a partition 3. The various component parts of the timer are assembled around the partition 3. The timer is designed, in the non-limiting example described, to cause the timed closing of contacts which have been shown in the form of a fixed contact 5 cooperating with a moving contact 6 carried by a rocker arm. The latter consists of a lever pivoted at 9, one end 7 of which carries the moving contact 6, while the other end is divided into two parts 17 and 17' forming a fork (see FIG. 2).

The bottom limb 17' of this fork carries an extension 16 equipped with a pin 10 parallel to the axis of rotation of the pivot 9 (FIG. 1).

The contact is closed by a spring 8 when this pin 10 has been released from a shoulder 11 on the limb 12 of a bolt which pivots at 14.

This bolt has a second limb 13. This limb 13 is itself in the shape of a fork (see FIG. 2) which bears on a cross-piece 15 connected to the movement of a bellows 21 by means of a return spring 18.

This cross-piece, shown in the "at rest" position in FIG. 1, can lift against a spring 20 when a thrust is exerted on a mobile plunger 19. At it moves, the cross-piece 15 moves the pivotal unit 7, 17, 16 clockwise, which causes the contacts to open and the pin 10 to lock on the shoulder 11. The timer proper comprises, besides the mobile plunger 19 and the spring 20, the aforementioned bellows 21, a front surface 22 of which is applied by spring action from inside against the partition 3 by an annular shoulder 23 on a coaxial cylindrical rod 24.

This cylindrical rod goes through an opening 45 in the front face 22 and an opening 46 in the partition 3; it also goes through an opening 47 in a timing device 26 integral with a rubber washer 27 and through an opening 48 in the bottom 40 of a rotary regulator 25. FIG. 1 shows that the regulator 25 and the timing device 26 are applied directly to each other and that the latter is applied against the partition 3 by means of the rubber washer 27, a spring component 39 and a washer 28, which is integrated with the rod 24.

One can say that the rod 24 and its annular shoulder 23, together with the washers 27 and 28 and the component 39, constitute a common spring means of maintaining the parts 21, 26 and 25 against the partition 3.

Moreover, ports can be seen at 30, 31, 32, 33, 34 and 35 which communicate with a throttling channel 36 formed in the surface of the timing device 26. The

ports, whose section can be of a size suitable to prevent dust or condensation from collecting, are moreover very short. The figure is not exactly to scale in order to make the drawing clearer, but it is easy to see that the lengths of these various ports can be very short. This is due to the relative positioning of the various components, which means that only the throttle of the throttling channel has to be taken into account for long times, even when the section of the other ports is decreased for some reason.

FIG. 1 shows a filter 29 whose diameter is very close to the width of the box. This filter is therefore large, and this has only been achieved due to the fact that the filter is positioned inside the cupel-shaped regulator 25. In fact, as the main surfaces of the box of the timer are either intended for purposes of mechanical or electrical connection or close to other instruments, it is not desirable to position the filter thereon.

The filter 29 is, moreover, fixed axially by a cover 37, itself fixed on the regulator 25 and, together with the latter, forming bent air intakes 38. These ports act as baffle plates against foreign bodies, while leaving a wide passing section for the fluid.

The working of the timer just described will now be explained with reference to FIG. 1. When the plunger 19 is pushed upwards, the air contained in the bellows 21 escapes downward between the said bellows and the said plunger. When the pressure on the plunger 19 ceases, the spring 20 applies the plunger 19 against the bottom of the bellows 21 and thus creates suction which spreads through the ports 34, 35, 33, 32 and 31, the throttling channel 36, the port 30, the filter 29 and the bent air intakes 38, into the open air.

The rotation of the regulator 25 brings the port 30 into a position opposite a certain portion of the channel 36 so that the distance covered by the fluid before it reaches the port 31 can change and the working time

be altered.

Many modifications can be made, either to the shape of the various components or to their position, without departing from the concept of the invention.

5 Thus, the partition 3 could form part of a removable unit (indicated by a dotted line in FIG. 1), so that the timers could be mounted separately and be fitted in boxes on which the contacts had already been mounted.

10 What we claim is:

1. An open-circuit pneumatic timer comprising, housed in a box having a wall, a bellows and spring means mounted inside said bellows for effecting expansion of the inside volume of said bellows, a timing unit mounted outside the box in proximity to said wall and provided with a throttling channel, an opening in said wall for connecting the inside volume of the bellows to the throttling channel, rotary means, mounted in contact with the timing unit, for adjusting the effective length of the throttling channel, said rotary means being in the form of a circular cupel having a bottom and an open part, an air filter mounted in the open part of said cupel, the bellows having frontal surface engaging said wall, the front surface of the bellows, said wall, the timing unit and the bottom of the rotary means being provided with openings, a rod member coaxial to the bellows mounted through said openings and having one end portion within the cupel, spring means mounted about said end portion and engaging the bottom of the cupel for securing together the said cupel the timing unit and the bellows about said wall.

2. A timer as claimed in claim 1, further comprising a removable cover mounted on the cupel and securing the filter, said cover being provided with a plurality of bent air intakes.
